UNITED STATES PATENT OFFICE.

JOHN R. HEEGER, OF SPRINGFIELD, OHIO.

CALIBRATING-MACHINE.

1,330,319.

Specification of Letters Patent. Patented Feb. 10, 1920.

Application filed April 19, 1919. Serial No. 291,186.

To all whom it may concern:

Be it known that I, JOHN R. HEEGER, a citizen of the United States, residing at Springfield, in the county of Clark and State of Ohio, have invented certain new and useful Improvements in Calibrating-Machines, of which the following is a specification.

The invention relates to a machine for 10 graduating collars, disks, and like work, the mechanism being such as to insure accuracy in the graduations and the lengthening of certain marks to facilitate the reading, whereby groups of indications are denoted.

15 The invention provides a machine of the character stated which may be readily adapted for marking collars or disks either on the face or edge, or for marking such parts having beveled edges upon which the 20 markings are to be indicated.

The drawings illustrate a preferred embodiment of the invention. However, it is to be understood that in adapting the same to meet different conditions, various changes 25 in the form, proportion, and minor details of construction may be resorted to without departing from the nature of the invention as claimed hereinafter.

Referring to the drawings hereto attached,

Figure 1 is a side view of a calibrating machine embodying the invention, the lower portion of the stand being broken away.

Fig. 2 is a top plan view.

35 Fig. 3 is a front view.

Fig. 4 is a rear view.

Fig. 5 is a horizontal section on the line 5-5 of Fig. 1.

Fig. 6 is a vertical section on the line 40 6-6 of Fig. 2 looking in the direction of the arrows.

Fig. 7 is a detail perspective view of the disk provided with an adjustable wrist.

Corresponding and like parts are referred 45 to in the following description and indicated in the several views of the drawings by like reference characters.

The machine comprises a stand 1 to the upper end of which is secured a bed 2 upon 50 which is mounted a head 3 and a post 4. The bed 2 is provided at one end with a vertically disposed sleeve 5 which is split at one side and adapted to be contracted by means of a clamp screw 6. The post 4 is 55 mounted in the sleeve 5 and is adjustable vertically and is secured in the adjusted po-

sition by contracting the sleeve 5 by means of the clamp screw 6. The post 4 is tubular and is prevented from turning in the sleeve 5 by means of a key 7 which coacts 60 with a groove formed in the inner wall of the sleeve 5. Rack teeth 8 are formed on one side of the post 4 and coacts with a pinion 9 provided on a shaft 10 which is mounted in bearings of the sleeve 5 and 65 which is provided at its outer end with a hand wheel 11. When the clamp screw 6 is loosened the post 4 may be vertically adjusted by operating the shaft 10 which rotates the pinion 9 and through the instrumentality of the rack teeth 8 raises or lowers the post. When the post 4 has been adjusted to the required position it is made secure by retightening the clamp screw 6 which contracts the sleeve 5 and binds the 70 post 4. A shaft 12 is rotatably mounted in the post 4 and is provided at its upper end with a flange 13 and a threaded stem 14, the flange 13 overlapping the post 4 to prevent downward displacement of the shaft 80 and the stem 14 being adapted to receive the work or a head 15 which terminates in a threaded stem 16 upon which the work may be secured, the head 15 formed as an extension of the shaft 12 which may be advantageous under certain conditions. A ring 17 is secured to the lower end of the post 4 below the sleeve 5 and supports a shaft 18 and a worm gear 19, the latter meshing with a worm 20 on the shaft 18. The worm gear 90 19 is keyed to the lower end of the shaft 12 so as to rotate therewith and is in mesh with the threads of the worm 20. The ring 17 and parts carried thereby move vertically with the post 4. A lever 21 is pivotally mounted upon the projecting end of the shaft 18 and is provided at one end with a spring actuated dog 22 and has a rod 23 pivotally connected with its opposite end. A ratchet wheel 24 is secured to the projecting 95 end of the shaft 18 so as to rotate therewith and is adapted to be intermittently actuated by means of the lever 21 through the instrumentality of the dog 22. It is proposed to have the ratchet wheel 24 detachably connected with the shaft 18 so that it may be replaced by a different ratchet wheel having a greater or a less number of teeth according to the specific work for which the machine is adapted. According to the number of teeth provided on the edge of the 100 ratchet wheel 24 the graduations of the

105

110

work will be coarse or fine as will be readily understood. Obviously provision is had for varying the movement of the lever 21 according to the number of teeth on the 5 ratchet wheel 24 as will appear more fully hereinafter.

The head 3 is slidable on the bed 2 and is adjusted by means of a screw 25 mounted on the bed 2 and a nut 26 depending from the 10 head 3 and entering a longitudinal depression formed in the bed 2 and in which is located the screw 25. A hand wheel 27 secured to the outer end of the screw 25 provides convenient means for rotating the 15 screw to effect adjustment of the head 3. A guide member 28 is pivotally connected to the head 3 to admit of the marker being adjusted to suit the nature of the work. The 20 guide member 28 is pivotally mounted upon a shaft 29 and is adapted to be secured in the adjusted position by suitable fastening means. The head 3 comprises a base and uprights and one of the latter is formed with an arcuate slot 30 in which operates a bolt 25 or like fastening 31. When the fastening 31 is loosened the guide member 28 may be turned on the shaft 29 to the required adjusted position to adapt the marker to the 30 work. One of the uprights of the head 3 has its edge formed on the arc of a circle concentric with the shaft 29 and provided with graduations 32, whereby to facilitate the setting of the guide member 28 when adjusting the same to a given angle. The 35 shaft 29 is provided at one end with a hand wheel 33 and at its opposite end with a disk or wheel 34 which is provided upon its outer side with a diametrical guideway 35 which receives an adjustable wrist 36 upon which 40 is mounted a sleeve 37 to which the rod 23 is adjustably connected. Adjustment of the wrist 36 in the guideway 35 to a greater or less distance from the axis of the shaft 29 results in varying the throw of the lever 21 and movement of the ratchet wheel 24 at 45 each operation thereof. When adjusting the post 4 vertically the means connecting the rod 23 to the sleeve 37 is loosened so that the rod 23 may move with the lever 21 in conformity to the vertical adjustment of the 50 post 4. When the post 4 has been adjusted to the required position it is made secure by operating the clamp screw 6 in the manner stated and the rod 23 is made fast to the 55 sleeve 37 so that in the rotation of the shaft 29 vibratory movement may be imparted to the lever 21, the rod 23 being connected to the sleeve 37 which in turn is loosely mounted on the wrist 36.

60 The guide member 28 receives a holder 38 which is mounted therein to receive a reciprocatory movement. The holder 38 carries the marker 39 which consists of a cutting tool such as usually provided in connection with machines for marking or calibrating

metal. The marker 39 is adjustable and detachable from the holder 38, whereby to admit of sharpening and replacement. A pin 40 projects laterally from the holder 38 and passes through a vertical slot 41 formed in a side of the guide member 28. A contractile helical spring 42 is connected at one end to the pin 40 and at its opposite end to a pin 43 which projects from the guide member 28. The pin 43 also serves as a stop to limit the downward movement of the holder 38. The holder 38 is moved vertically by means of a toothed wheel 44 which is mounted on a pin 45 carried by the guide member 28. The teeth of the toothed wheel 44 co-operate with the holder 38 to move the same upward against the tension of the spring 42. A wheel 46 is secured on the shaft 29 to rotate therewith and is provided with a pin 47 which is adapted to engage the teeth of the 85 wheel 44 and impart an intermittent rotary movement thereto, whereby to effect a reciprocating movement of the holder 38 and the marker carried thereby. The wheel 44 may be provided with any number of teeth, 90 but one tooth as 44^a is made longer than the remaining teeth to lift the holder 38 a greater distance, whereby the mark made by the element 39 is longer than the remaining marks. Thus the graduations are indicated 95 in groups with the result that the reading is greatly facilitated. As indicated most clearly in Fig. 6 the wheel 44 is provided with four short teeth of equal length and one long tooth, hence the graduations will have every 100 fifth mark longer than the remaining marks, whereby the indications may be read quickly in groups of five.

The work may be secured on the stem 14 or the stem 16 after which the post 4 is adjusted vertically to bring the work to the required level. The head 3 is moved in or out by means of the screw 25 so that the marker 39 may be adjusted to the work. When the marks are to be formed on the edge of a 110 disk, wheel or collar which is parallel with the axis of the part, the guide member 28 is adjusted to cause the holder 38 to reciprocate in a direction parallel with the axis of the shaft 12. If the edge of the collar, disk or 115 like part is inclined the guide member 28 is adjusted to the proper angle so that the cutting edge of the marker 39 will engage the edge of the work. If the graduations are to be formed on a side of the disk, collar or the like, the guide member 28 is turned to occupy a horizontal position, whereby the marker 39 will operate in a plane at a right angle to the axis of the shaft 12. It is to be understood that the post 4 will be adjusted vertically to bring the work in proper position with reference to the marker 39 and the head 15 may be disconnected from or attached to the shaft 12 as may be found most advantageous. After the work has been secured to 130

the shaft 12 the machine is operated by rotating the shaft 29 which imparts a reciprocating movement to the marker and an intermittent rotary movement to the shaft 5 12 through the intermediate connections such as the worm gearing, ratchet mechanism, lever 21 and connecting rod 23.

The foregoing description and the drawings have reference to what may be considered the preferred, or approved form of my invention. It is to be understood that I may make such changes in construction and arrangement and combination of parts, materials, dimensions, etc., etc., as may prove expedient and fall within the scope of the appended claims.

Having thus fully described my invention, what I claim as new and desire to secure by Letters Patent is:—

20 1. In a calibrating machine of the character specified, the combination of a rotary work holder mounted for relatively vertical adjustment, means for securing the work holder in the required adjusted position, a 25 reciprocating marker mounted for angular adjustment, means for securing the marker in the adjusted position, operating means for imparting an intermittent rotary movement to the work holder including a ratchet 30 mechanism, operating means for the marker including a rotary toothed member, and connecting means between the said ratchet mechanism and rotary toothed member for transmitting motion from one to the other 35 in any adjusted position of the work holder and marker.

2. In a calibrating machine of the character specified, the combination of a vertically adjustable post, a work holder carried by 40 the post and rotatable therein and mechanism carried by the post and adapted to transmit an intermittent rotary movement to the work holder at any relative adjusted position of the post.

45 3. In a calibrating machine of the character specified, the combination of a vertically adjustable post, a work holder carried by the post and rotatable therein, a gear element carried by the post, a companion gear 50 element rotatable with the work holder and in coöperative relation with the gear element carried by the post and means for imparting movement to the gear element carried by the post at any relative adjusted 55 position thereof.

4. In a calibrating machine of the character specified, the combination of a vertically adjustable post, a work holder carried by the post and rotatable therein, gearing carried 60 by the post for imparting rotary movement to the work holder, a reciprocating marker and adjustable connecting means between the marker and gearing carried by the post for operating the work holder at 65 any relative adjusted position of said post.

5. In a calibrating machine of the character specified, the combination of a supporting member including a clamp sleeve, a post adjustable in the clamp sleeve and adapted to be secured thereby in the adjusted position, a work holder rotatable in the post, a gear element carried by the post and a co-operating gear element rotatable with the work holder. 70

6. In a calibrating machine of the character specified, the combination of a post mounted for relative vertical adjustment, a work holder rotatable in the post, worm gearing carried by the post and adapted to transmit movement to the work holder, a 80 lever mounted in line with the gear element supported directly by said post, a ratchet mechanism between the said lever and the gear element co-axial therewith and means for imparting a vibratory movement to the 85 lever.

7. In a calibrating machine of the character specified, the combination of a post mounted for relative vertical adjustment, a work holder rotatable in the post, worm 90 gearing carried by the post and adapted to transmit movement to the work holder, a lever mounted in line with the gear element supported directly by said post, a ratchet mechanism between the said lever and the gear element co-axial therewith and means for imparting a variable vibratory movement to the lever. 95

8. In a calibrating machine of the character specified, the combination of a relatively 100 vertically adjustable post, a work holder rotatable therein, worm gearing carried by the post and comprising a worm and worm gear, the latter being connected to the work holder for rotation therewith, a lever mounted in 105 line with the worm, a ratchet wheel connected with said worm for rotation therewith and a dog carried by said lever and in coöperative relation with the ratchet wheel.

9. In a calibrating machine of the character specified, the combination of a clamp sleeve, a post adjustable in the clamp sleeve, post adjusting means carried by the post and clamp sleeve, a work holder rotatable in the post, a worm gear connected with the work 115 holder, a worm carried by the post and in coöperative relation with the worm gear and means for imparting a rotary movement to the worm.

10. In a calibrating machine of the character specified, the combination of a clamp sleeve, a post adjustable in the clamp sleeve and provided in its length with rack teeth, a pinion mounted on the clamp sleeve and in mesh with said rack teeth, a work holder rotatable in the post, a worm gear connected with the work holder, a worm carried by the post and in coöperative relation with the worm gear and means for imparting rotary movement to the worm. 120
125
130

11. In a calibrating machine of the character specified, the combination of a rotary work holder mounted for relative vertical adjustment, a reciprocatory marker, means for imparting a reciprocating movement to the marker including an element provided with a wrist adjustable toward and away from the center of said element and means adjustably connecting said wrist with the work holder operating means.
12. In a calibrating machine of the character specified, the combination of a rotary work holder, means for imparting an intermittent rotary movement to the work holder and including a variable ratchet mechanism, a reciprocatory marker, means for imparting a reciprocating movement to the marker and including a rotary element, a wrist having adjustable connection with said rotary element and connecting means between said wrist and the ratchet mechanism for operating the work holder.
13. In a calibrating machine of the character specified, a work holder, a supporting member, a guide member pivotally connected to the supporting member to admit of angular adjustment and a reciprocating marker mounted upon said guide member.
14. In a calibrating machine of the character specified, the combination of a work holder, a supporting member, a shaft mounted upon the supporting member, a guide member pivotally mounted on the shaft, means between the guide member and supporting member for securing the guide member in the angular adjusted position and a reciprocating marker mounted upon said guide member and adapted to be operated from the said shaft.
15. In a calibrating machine of the character specified, the combination of a bed, a

work holder mounted upon the bed, a head adjustable on the bed toward and away from the work holder, a guide member carried by said head and capable of angular adjustment and a marker mounted upon the guide member.

16. In a calibrating machine of the character specified, the combination of a bed, a work holder mounted upon the bed and adapted to be adjusted in a relative vertical direction thereto, a head adjustable on the bed toward and away from the work holder, a guide member carried by said head and adapted to be adjusted angularly with reference to the work holder and a reciprocating marker carried by the said guide member.

17. A calibrating machine of the character specified, comprising a bed, a rotary work holder carried by the bed, means for adjusting the work holder vertically and securing the same in the required adjusted position, a head adjustable on the bed toward and away from the work holder, a guide member carried by the head and adapted to be adjusted angularly, a reciprocating marker mounted upon the guide member, mechanism mounted upon said head for imparting a reciprocating movement to the marker and adjustable connecting means between the operating mechanism and the work holder for actuating the latter at any relative adjusted position and to meet requirements of the work.

In testimony whereof I affix my signature in presence of two witnesses.

JOHN R. HEEGER.
